UNITED STATES PATENT OFFICE.

CORODEN J. SLAFTER, OF GRAND JUNCTION, MICHIGAN.

CAR-LABEL HOLDER.

SPECIFICATION forming part of Letters Patent No. 256,248, dated April 11, 1882.

Application filed December 29, 1881. (No model.)

To all whom it may concern:

Be it known that I, CORODEN J. SLAFTER, a citizen of the United States, residing at Grand Junction, county of Van Buren, State of Michigan, have invented a new and useful Car-Label Holder, of which the following is a specification.

The object of my invention is to construct a device adapted for connection with a railroad freight-car, by means of which the labels and cards used to designate the contents and destination, &c., of a car may be securely and more readily attached to the same than by previously-devised means.

15 My invention consists of a plate provided with spurs and a clamping device adapted for forcing the card onto said spurs and holding it securely, the whole being adapted for connecting with the outside of the wall of a box-car or the frame of a flat car.

20 In the drawings forming a part of this specification, Figure 1 is a perspective view of my device detached from the car; Fig. 2, a front view with the device attached to a car-wall; Fig. 3, the same holding a label, and Fig. 4 a cross-section on dotted line in Fig. 2.

25 B is the plate, having arms y y. The clamp proper, s, is formed from a piece of spring-wire. At v it is bent outward, forming a handle to operate it by. The wire is coiled around arms y y, forming helices c c, from which the two ends extend down the back side of plate B in grooves e e, and terminate in sharp spurs a a, projecting through holes in said plate. Thus 30 the clamp and spurs are all made of a single piece of wire, which, should it become broken, can be detached from its support B and readily replaced with another.

The helices form convenient means of connecting the clamp with the plate, and add 40 greatly to the elastic force of said clamp.

By securing the device to the car by screws t t or other practical means the spurs are kept out in place.

In the operation clamp s is sprung out from 45 the plate or car, as in Fig. 1, by the operator standing on the ground by the side of the car, (as the car moves past him, or otherwise,) and card or label D is inserted between the plate and clamp, when the latter is released, which 50 by its elastic force or power forces the label onto the spurs and retains it securely, as before stated.

Having thus described my invention, what I claim as new, and desire to secure by Letters 55 Patent, is—

1. A label-holder consisting of a plate provided with arms for supporting a clamp, a clamp coiling around each of said arms, forming springs, and extended vertically therefrom 60 and passed through the plate, terminating in spurs adapted to receive the label on the front face of said plate, where it is held by the clamp-arms, all substantially as described, for the purpose set forth.

2. The combination, substantially as set forth, of the plate with its arms and rear grooves and holes for the spurs, and the clamp having the handle, the helices, and the extended ends with the spurs, all adapted for the 70 purposes set forth.

CORODEN J. SLAFTER.
